(57) **CLAIM**

The ornamental design for a shoe outsole bottom, as shown and described.

DESCRIPTION

FIG. 1 is a top perspective view of a shoe outsole bottom in accordance with my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a bottom perspective view thereof.

The broken lines shown in the drawings represent portions of the shoe outsole bottom and environmental structure in the form of a shoe upper and midsole that form no part of the claimed design.
